UNITED STATES PATENT OFFICE.

HAROLD HERBERT, OF LISCARD, WALLASEY, ENGLAND.

SEWING-MACHINE.

1,180,037.

Specification of Letters Patent. Patented Apr. 18, 1916.

Application filed October 9, 1914. Serial No. 865,919.

To all whom it may concern:

Be it known that I, HAROLD HERBERT, a subject of the King of England, residing at 2 Maldwyn road, Liscard, Wallasey, in the 5 county of Chester, England, have invented new and useful Improvements in Sewing-Machines, of which the following is a specification.

This invention has reference to sewing machines, and more particularly to such machines as are constructed and adapted for repairing cuts, holes or similar damage in textile and other similar goods or articles, of the kind in which is employed a rank of 15 sewing needles and an under needle or looper, and a device for concatenating the loops of the under needle thread.

A machine according to this invention, comprises two sets of needles, preferably 20 each set consisting of a plurality of needles, separately operated, and adapted to strike and act alternately on the material which is to be "sewn"; and operating in connection with these needles is a needle or device 25 below the throat plate or table over which the work passes, adapted to pass a thread through all the several loops formed by the sets of the upper needles; and also to form a loop in this thread at its outer end, which 30 loop is engaged by the under thread in its next pass, that is, this thread in each passage is passed through the former loop made in the next preceding passage of the under needle or device, and so is locked, and so on, 35 the action is repeated.

In the drawings, illustrating the invention, Figure 1 is a side elevation, showing a machine adapted to operate according to the method above described; Fig. 2 is a plan of 40 a part of it; and Fig. 3 is a detail view of the under needle or device. Fig. 4 is a section on the line 4—4 of Fig. 2. Fig. 5 is a detail vertical section on the line 5—5 of Fig. 4. Fig. 6 is a similar view on the line 45 6—6 of Fig. 4. Fig. 7 is an enlarged diagrammatic perspective view of the stitches produced by the machine.

In these drawings, *a* is the machine arm; *b* is one set of needle rods, and *c* the other; 50 *b*¹ and *c*¹ being respectively the needles fixed in the ends of these rods.

The needle rods are guided in the machine arm *a* and the several rods which form each set, are connected together on opposite 55 sides of the machine, by a connecting plate *d*; and these plates are worked up and

down alternately through connecting rods *e* which may be actuated by any suitable known mechanical motion, causing the two sets of needles—of which there are three in 60 each set in the case shown—to move down and up, alternately.

The throat plate over which the work is passed, is marked *f*; and in the plane in which the needles *b*¹, *c*¹ lie, there is an elongated slot *g* in this plate through which these needles pass. Beneath the plate *f*, is a needle *h* by means of which a thread is passed through the loops formed by the needles *b*¹, *c*¹. This needle, as shown in 70 plan, is preferably flat at one side, and this flat part works across the sides of the needles; and at its front end, it is provided with an open eye marked *i* in the form of a crotch; and this crotch is adapted to engage 75 the under thread as the needle *h* is pressed forward in its active stroke, and push the thread through the loops which will have been formed by the threads of the upper needles *c*¹, and *b*¹, as the case may be; these 80 needles being supplied with thread or sewing material in the usual way.

The needle *h* will be moved to and fro by any suitable motion, which will reciprocate it to and fro at the required moments; and 85 at the outer end of its stroke, when it passes the last needle, it will leave a loop *k* of the thread which it has moved through the loops *l* of the needle threads; and, preferably, this loop will be engaged by a suitable holding 90 hook *m* when this needle *h* returns, and the loop *k*, will thus be held when the work passes along, so that when the work has been moved to the next position, this loop will be 95 in line with the needle *h*, and the thread which it then passes through the needle loops in the next action, will be passed through this loop, and so engage and lock the under thread so that a species of chain lock stitch 100 of the under thread is effected. The whole or complete "sewing" effect produced is a species of darning.

By reference to the diagram shown in Fig. 7, it will be seen that the heads of the adjacent loops *k* are on opposite sides of the work, and that the loops *l* formed by the needles *c*¹ engage one set of loops *k*, while the loops *l*, formed by the needles *b*¹ engage the adjacent or alternate loops *k*. By this means the stitches formed by the two sets of needles can be placed close together without 110 weakening the fabric, as the loops *l* of the

respective adjacent stitches in the fabric are staggered or out of horizontal alinement. Hence a machine constructed in accordance with this invention may be employed advantageously for repairing or strengthening a piece of fabric, and furthermore, various designs on the surface of the fabric can be produced by using different colored threads in the respective sets of needles.

10 What is claimed is:—

1. In a sewing machine, the combination of two sets of alternately operated needles, a plate formed with an opening for the passage of the needles, means for passing a looped thread through all the loops of each set of needles when the latter are driven down below the plate, and means for holding the looped thread while the loop forming means is withdrawn.
- 15 2. In a sewing machine, the combination of two sets of needles to form alternate rows of loops, means for inserting a continuous looped thread through each successive row of loops, and means for holding the looped thread while the respective rows of loops are drawn into the material.
- 20 3. In a sewing machine, the combination

of two sets of alternately operated needles, a plate having an opening for the passage of the needles, a horizontally disposed needle located under the throat plate to form an elongated loop in the row of loops formed by each set of needles, and means for holding the looped thread while the horizontal needle is being withdrawn.

35 4. In a sewing machine, the combination of a needle for forming from a continuous thread a plurality of elongated loops, the connecting portion of each loop extending from one leg of one loop to the leg of the adjacent loop, and two sets of alternately operated needles, one set of needles forming loops around the legs of one set of elongated loops, and the other set of needles forming loops around the legs of the other set of elongated loops.

35 In testimony whereof I have signed my name to this specification in the presence of two subscribing witnesses.

HAROLD HERBERT.
